UNITED STATES PATENT OFFICE.

CHARLES N. CADWALLADER, OF PHILADELPHIA, PENNSYLVANIA,
ASSIGNOR TO O. F. DAVIS, OF SAME PLACE.

IMPROVEMENT IN CANDLE-HOLDERS.

Specification forming part of Letters Patent No. 150,283, dated April 28, 1874; application filed
March 9, 1874.

To all whom it may concern:

Be it known that I, CHARLES N. CADWALLADER, of the city and county of Philadelphia, and the State of Pennsylvania, have invented a new and useful Improvement in Candle-Holders; and I do hereby declare the following to be a clear and exact description of the nature thereof, sufficient to enable others skilled in the art to which my invention appertains to fully understand, make, and use the same, reference being had to the accompanying drawings making part of this specification, in which—

Figure 1 is a central vertical section of the device embodying my invention. Fig. 2 is a side elevation thereof.

Similar letters of reference indicate like parts in the two figures.

The subject of this invention is a candle-holder formed with a series of pins of differential lengths projecting from a tray or pan, so that when a candle is shortened by burning, and the longer pins become heated, it will be still held by the shorter pins. A stem projects downward from the tray, and is adapted to fit the socket of a candlestick.

Referring to the drawings, A represents a tray or pan, which is somewhat conical or dished, and constitutes the base of the candle-holder. From the upper side of the tray there projects a series of pins, B B, which are arranged in circular order, or of such order that there is left within the pins a space for the reception of the lower portion of a candle, which portion will be embraced by the pins B.

It will be seen that by these means the candle will be firmly held in place, and when it burns below the top of the pins the light will shine therethrough, so that the candle may be burned to its very bottom, whereby there is no loss of light and stumps are not left.

C represents a series of pins, which are shorter than the pins B, said pins C project-

ing upwardly from tray A, and are arranged in order similar to the series B, alternating with the said series B.

It will be seen that when the candle has burned below the top of the long pins B the flame will heat said pins, whereby the portion of the candle in contact therewith will melt. The candle, losing the support originally imparted by the long pins, would fall or totter were it not that the short pins C, not being within reach of the flame, continue to hold the lower portion of the candle, and thus the candle will be maintained upright throughout, for, by the time the short pins become heated sufficiently to affect the candle, the latter is about burned out, or the melted matters that have collected in the tray A are sufficient to hold the small piece of the unconsumed candle.

A stem may be formed with the tray on the under side thereof, in order to apply the holder to a candlestick, or the holder may constitute the top of a candlestick. The stem may likewise be pointed or screw-threaded, for application to places where a candlestick is not required.

The melted matters from the candle will be retained in the tray A, whose dished shape prevents the overflow of said matters.

Having thus described my invention, what I claim as new, and desire to secure by Letters Patent, is—

A candle-holder consisting of a tray or pan with a downwardly-projecting stem, a series of long pins projecting upward from the tray or pan, and adapted to embrace the candle, and a series of short pins, alternating with the long pins, and likewise adapted to embrace the candle, substantially as herein set forth.

CHARLES N. CADWALLADER.
